UNITED STATES PATENT OFFICE.

SAMUEL Q. WILKINSON, OF BELLE VERNON, PENNSYLVANIA.

ACID-TANK.

1,036,761.

Specification of Letters Patent. Patented Aug. 27, 1912.

Application filed April 11, 1911. Serial No. 620,516.

To all whom it may concern:

Be it known that I, SAMUEL Q. WILKINSON, a citizen of the United States, residing at Belle Vernon, in the county of Fayette and State of Pennsylvania, have invented 5 certain new and useful Improvements in Acid-Tanks, of which the following is a specification.

My invention relates to improvements in 10 acid tanks, and has for its leading object the provision of an improved acid tank for use in removing scale from metal rods.

Another object of the invention is the provision of an improved tank of this character 15 provided with means for readily filling and emptying the tank to prolong the life of the bottom of the tank.

A further object of the invention is the provision of an acid tank for removing 20 scales from bundles of iron rods having an improved construction of brace supports for the member carrying the rods and having improved reinforcing portions for the rod support to prevent wearing of the ends of 25 the support.

To attain the above and other objects which will be apparent from the following description I have provided an acid tank and rod support substantially as hereinafter 30 described and as illustrated in the accompanying drawing, but it will be understood that I may make any changes in the specific construction shown within the scope of the claims without departing from or exceeding 35 the spirit of the invention.

Figure 1 represents a side elevation of my improved tank. Fig. 2 represents a top plan view thereof. Fig. 3 represents a longitudinal sectional view with the rod supporting 40 beam in position. Fig. 4 represents a cross sectional view thereof. Fig. 5 represents a sectional view of the end of the beam and cap plate, and Fig. 6 represents a plan view of the spraying belt with the beam resting 45 thereon.

In the drawings, the numeral 1 designates the planks forming the bottom of my tank, having rising therefrom the side forming planks 2 and the end planks 3, there being a 50 plurality of bolt rods 4 passing vertically through the middle of the various planks to secure them together, the planks thus being disposed on each side of the bolt rods to protect the rods from the eating action of the 55 acid contained in the tank, while at the same time the position of said rods prevents warp-

ing or displacement of the planks. To brace the bottom I secure therebelow the transversely extending wooden beams 5 through which certain of the bolt rods 4 pass, transversely extending bolt rods 6 passing through the sides and end planks to secure them in desired position.

To facilitate the filling or emptying of the rectangular wooden receptacle thus formed, 65 in place of forming merely a plugged opening in the bottom to drain the same, as is now the common practice, which opening rapidly becomes enlarged and soon impairs the usefulness of the bottom, I have provided an improved filling and emptying pipe. Projecting upward through the bottom planks 1 and flushed with the upper face thereof is the pipe 7 having the locking washers 8 engaging the upper and lower 70 faces of the bottom plank to provide a tight joint, while secured to the lower end of the pipe is the elbow 9 into which is screwed the horizontally extending pipe 10 having connected to its outer end exterior to the tank 75 the elbow 11 retained by the pivotal coupling 12 which permits the elbow to swing around on the pipe 10, a pipe 13 of length greater than the height of the tank being secured to the free end of the elbow 11. To fill the 80 tank and prevent the dangerous splashing of the acid caused by directly pouring the acid into the tank, I place the pipe 13 in vertical or substantially vertical position and secure 85 it there by the locking member 14 projecting from the side of the tank, and I then pour the acid into the upper end of said pipe the acid flowing down and through the connected pipes and up into the interior of the tank to thoroughly engage the rods suspended in the tank. To empty the tank the pipe 13 is swung on the pivot connection 12 until its end is lower than the pipe 10, when the acid will flow from the tank through the 90 various pipes and be discharged from the 100 pipe 13.

To support the rods to be treated within the tank and prevent the lower ends of the supporting members from being quickly 105 driven through the bottom of the tank as frequently occurs with the type of support at present in general use, I secure at the bottom of the tank near each end the transversely extending beam 15 having ends making mortise and tenon engagement with the sides of the tank, while rising centrally from the beam 15 is the post 16 having its 110

end engaged respectively in the beam 15 and in the transverse beam 17 disposed intermediate the height of the tank and having its ends mortised in the sides of the 5 tank to further brace the same. Resting upon and slightly inlaid in the beam 17 is the horizontal portion 18 of the L-shaped plate 19 which extends upward to the upper edge of the tank and has the outwardly 10 and downwardly bent end 20 fitting over the upper edge of the end of the tank to both protect the end of the tank and support the portion 18 of the plate.

Secured to the tank at one side of the 15 plate 19 is the guide member 21 having the upper inclined end 22 and having its lower end mortised in the beam 17. In the use of the tank, I suitably lower the stem beam 23 bearing the bundles of rods 24 into the 20 tank, the ends of said beam being guided into position by the guide member 21, while the plate 19 engages the ends of the beam to prevent the same from rubbing against the readily worn planks 3 and the plate 25 end 18 reinforces the beam 17 and aids in supporting the stem beam 23.

To prevent the ends of the stem beam 23 from rapidly wearing, I mount thereon the loosely fitting rectangular collars 25 having 30 the upwardly projecting lugs 26 formed with the aperture 27 to receive the lifting hook of a crane. These collars 25 are further useful to protect the ends of the beam when the same is placed upon the 35 chains 28 of the spray belt, the collars 25 resting on the chains while the stem beam and rods 24 hang between the chains 28 where the rods will be struck by the cleansing spray.

40 From the foregoing description taken in connection with the drawings, the construction of my improved acid tank will be readily understood, and it will be seen that I have provided a tank of extremely simple 45 and durable construction in which the securing rods are set in the beams and thus protected from the action of the acid while so bracing and securing the parts of the tank together as to securely brace the side 50 and other parts of the tank, while preventing the warping thereof. It will further be seen that I have obviated the danger of the acid splashing and also prolonged the life of the bottom of the tank by providing 55 an open pipe at the bottom thereof having an end adapted for use in one position for filling the tank and in another position as a discharge pipe for the tank, while to

protect the bottom from the wearing action of the stem supporting posts, I have provided an improved construction of reinforced rod supports and have further provided an improved combination reinforcing collar and lifting eye for the ends of the stem beam which may be quickly applied 60 thereto.

The advantages of my improved acid tank and rod supporting stem will be fully apparent from the foregoing description taken in connection with the drawings, and 70 it will be seen that I have provided a simple and efficient acid tank of thoroughly practical and economical construction which will commend itself to all those familiar with the construction of ordinary acid tanks as 75 being a great improvement thereover.

I claim:

1. An acid tank, comprising a wooden receptacle, a transverse bracing beam secured to the bottom of the receptacle at each end, 80 a vertical support rising from said transverse beam, a transverse beam mounted on the support and having its ends mortised in the sides of the tank, a bracing plate extending over the upper edge of the end of the tank and having a depending L-shaped 85 arm extending down the side of the tank and resting on the upper transverse beam, and a guide member secured at the side of the plate to the end of the tank and resting 90 on the beam adjacent the plate, said guide having an outwardly tapering upper end.

2. An acid tank, comprising a wooden receptacle, metal bolt rods passing through adjacent sections of the receptacle and having their body portions entirely inclosed by the wood of said sections, a combined inlet and discharge pipe for the tank, an interior bracing structure formed on and rising from the bottom of the tank, said structure comprising a pair of transverse beams and a support connecting the same, a reinforcing plate inlaid in the upper beam and extending upward and over the edge of the end of the receptacle, guides adjacent said plates, 100 and a longitudinally extending supporting beam mounted on the inlaid plate and having reinforcing metal members resting on the plate and provided with upwardly projecting eyes to receive a lifting device. 105

In testimony whereof I affix my signature, in the presence of two witnesses.

SAMUEL Q. WILKINSON.
